UNITED STATES PATENT OFFICE.

CHARLES T. McELVANEY, OF DENISON, TEXAS, ASSIGNOR OF ONE-HALF
TO MARK McCOMAS, OF DENISON, TEXAS.

HEADLIGHT ATTACHMENT.

No. 855,122.

Specification of Letters Patent.

Patented May 28, 1907.

Application filed January 8, 1906. Serial No. 295,064.

To all whom it may concern:

Be it known that I, CHARLES T. McELVANEY, a citizen of the United States, residing at Denison, in the county of Grayson and State of Texas, have invented new and useful Improvements in Headlight Attachments, of which the following is a specification.

My invention pertains to devices for displaying numbers or other signals in front of locomotive headlights; and it has for one of its objects to provide a simple device for the purpose indicated embodying such a construction that there is no liability of the numerals or other signals being obstructed or rendered obscure by dirt or other substance.

Another object of the invention is the provision of a device in which no glass or other fragile material is employed, and one adapted to be readily positioned on and attached to locomotive headlights.

Another object is the provision of a device constructed in such manner that when it is necessary to change the headlight from one locomotive to another, plates bearing the numerals or other signals may be expeditiously and easily removed and replaced with plates bearing other numerals or signals.

Other advantageous features peculiar to my invention will be fully understood from the following description and claims when the same are considered in connection with the accompanying drawings, forming part of this specification, in which:

Figure 1 is a view illustrating a portion of a locomotive headlight and my novel display device in proper position thereon. Fig. 2 is an enlarged view of the device removed; the same being shown partly in horizontal section and partly in inverted plan. Fig. 3 is a transverse section taken in the plane indicated by the line 3-3 of Fig. 2 but showing the device in its proper operating position.

Similar letters designate corresponding parts in all of the views of the drawings, referring to which:

A is a locomotive headlight having the usual circular body *a* and lens-holding rim or flange *b*; and B is the body of my novel display device. The said body B is preferably made of sheet-metal in the general form illustrated; and comprises a top wall *c*, a back wall *d*, a front wall *e*, side walls *f* fixed to the top, back and front walls and converged from the said back wall to the front

wall, and a longitudinal central, vertically disposed partition wall *g* fixed to the top wall and the front wall and extending rearwardly from the latter about the proportional distance illustrated.

The back wall *d* of the body B is provided with a rearwardly extending flange *h* which describes a part of a circle and is designed to rest on and be attached to the perimeter of the headlight body *a*, while the side walls *f* of said body B are equipped at their lower rear corners with lugs *k* arranged to bear on and be attached, if necessary, to the rim or flange *b* of the headlight body after the manner clearly illustrated in Fig. 1.

In the side walls *f* of the device body B openings *l* of about the proportional size illustrated are provided. These openings *l* are preferably though not necessarily rectangular in form, and are bordered by keeper flanges *m* which comprise horizontal portions fixed to the side walls *f* along the lower walls of the openings and upright portions disposed at the opposite ends of the openings. These keeper flanges *m* are designed to receive and hold plates *C* in which the numerals or other signals *D* are cut as shown; and by virtue of the said plates being arranged in the keeper flanges, it will be apparent that when it is necessary to change the headlight from one locomotive to another, the plates *C* may be removed with facility and as readily replaced with other plates provided with the proper numerals or other signals.

The lower side of my novel device or rather the body B thereof is open throughout its area and the openings *l* in the side walls of said body are occupied by the plates *C*. By virtue of this it will be apparent that the interior of the body B will be illuminated by the locomotive headlight, and the light will stream out through the openings *D* representing numerals or other signals with the result that the said numerals or signals will be plainly visible at all times and under all conditions of weather.

With a view of rendering the numerals or other signals cut in the plates *C* more plain and prominent I contemplate painting or otherwise making the interior of the body B light in color. This is particularly advantageous when the partition wall *g* is employed in the body B for then it will be observed that the illumination afforded by the locomotive headlight will enable the said par-

tion wall *g* to increase the prominence of the numerals or other signals cut in the plates *C*.

It will be gathered from the foregoing that the numerals or other signals *D* provided in the form of openings in the plates *C* are not liable to be obstructed or rendered obscure by dirt or other substance, and hence my novel device requires but a minimum amount of cleaning, and may be depended on to properly display the engine number or other signals at all times. It will also be gathered that my novel device is at once inexpensive, light and well adapted to withstand the usage to which locomotive devices are ordinarily subjected, and that it embodies no glass or similar material which is liable to be broken after a short period of use and requires frequent cleaning.

By virtue of my novel device being positioned on the locomotive headlight in the manner shown in Fig. 1, the device is illu-

minated in the manner and for the purpose before described, and yet does not in any degree obstruct the locomotive headlight.

I claim:

The combination with an illuminating device having a lens; of a signal display device fixed with respect to the illuminating device and comprising a box-like body arranged above and extending forward of the lens at a right angle thereto, the said body having openings in its upright walls forming signals and being open at its under side throughout its area in front of the lens, and also having an upright partition intermediate said upright walls.

In testimony whereof I have hereunto set my hand in presence of two subscribing witnesses.

CHARLES T. McELVANEY.
